CLAIM

The ornamental design for a gun rack, as shown and described.

DESCRIPTION

FIG. 1 is a front and top perspective view of a gun rack showing my new design.

FIG. 2 is a rear and bottom perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof; and,

FIG. 9 is an exploded view thereof.

The broken lines in the drawings depict portions of the gun rack that form no part of the claimed design.

1 Claim, 9 Drawing Sheets
